UNITED STATES PATENT OFFICE.

NORMAN T. HARRINGTON, OF LANSING, MICHIGAN.

VALVE-CONTROL MECHANISM FOR EXPLOSION-ENGINES.

962,214*

Specification of Letters Patent. Patented June 21, 1910.

Application filed January 20, 1908. Serial No. 411,739.

To all whom it may concern:

Be it known that I, NORMAN T. HARRINGTON, a citizen of the United States of America, residing at Lansing, in the county 5 of Ingham and State of Michigan, have invented certain new and useful Improvements in Valve-Control Mechanism for Explosion-Engines, of which the following is a specification, reference being had therein 10 to the accompanying drawings.

It is the object of the invention to obtain a construction of controlling mechanism for valves of explosion engines by which the valves may be readily adapted for operating 15 with different gases; for instance, if the engine as originally designed is intended for the use of manufactured gas a slight adjustment adapts it for the use of natural gas or for a gas from a suction producer.

20 The invention consists in the means employed for controlling separately the gaseous ingredients forming the explosive mixture, as for instance air and the fuel gas; further in the means whereby the separate 25 controlling valves are simultaneously operated and correspondingly timed; further in the means by which the amplitude of movement of said valves is correspondingly automatically varied with variations in the load; 30 and, further, in the means for adjusting the relative degree of movement of the separate valves without effecting either the timing thereof or the corresponding adjustment of the engine by the automatic control.

35 In the drawings Figure 1 is a side elevation, partly in section, of my improved valve operating and controlling mechanism; Fig. 2 is a plan view thereof, also partly in section; Fig. 3 is a diagrammatic view illustrating a modified construction.

40 A is the engine cylinder containing the mixing chamber A', and B is the main admission valve controlling the port from the mixing chamber into the cylinder proper.

45 C is a casing connected to the cylinder and communicating with the mixing chamber A', this chamber being divided by partitions into separate compartments C', D and E. The compartments D and E are respectively connected with inlet conduits for 50 air, gas or other gaseous ingredients of the explosive mixture, and F and G are valves

preferably puppet valves controlling ports connecting the chambers D and E with the chamber C'.

55

The operating mechanism for the valves F and G comprises a rod H operated by any suitable mechanism (not shown) and controlled by any suitable construction of automatic governor so that the stroke is varied 60 in amplitude with varying loads of the engine. The particular construction of this governing mechanism forms no part of the present invention and is therefore not illustrated in the drawings, as various constructions well known in the art may be employed for this purpose. The rod H is also employed for operating the main inlet valve B of the engine, and to this end is connected to a rock arm I which operates a rock shaft 70 J, the latter being connected through the medium of compound levers or rock arms K and L to a second rock shaft M. This shaft M has secured thereto two rock arms N for respectively operating the valves F and G 75 through the medium of bell crank levers P P'. Each of these bell crank levers has secured to one arm thereof an adjustable bearing Q, preferably a roller bearing, which contacts with the corresponding rock 80 arm N, whereby the degree of movement imparted therefor to the bell crank levers is changed. The opposite arms of the bell cranks P, P' contact with the stems R of the valves F and G respectively, and springs 85 S serve to seat the valves and actuate the bell cranks in the opposite direction.

90 In operation the movement of the valve rod H is transmitted to each of the valves B, F and G, which are operated simultaneously thereby, and are timed for the proper operation of the engine. The degree or amplitude of movement given to each valve depends first upon the amplitude of movement of the rod H, this being varied by the 95 governor in the usual way, as for instance, by the shifting of an eccentric. The amplitude of movement of the valves F and G is however further dependent upon the particular adjustment given to each of the adjustable bearings Q and the bell crank levers P. Thus if these bearings are adjusted into 100 similar positions on their bell cranks the amplitude of movement of the two valves

F and G will be the same, and may be more or less in relation to the movement of the valve B. On the other hand, if the bearings Q are differently adjusted upon the bell 5 cranks N N', as illustrated in Fig. 1, the movement imparted to one of the valves, as G, will be greater than that of the other valve F, but with each and every adjustment both of the valves will be simultaneously seated and unseated by the operation of the rod H.

By means of the construction and adjustments just described, the proportion of the ingredients composing the explosive mixture 15 may be adjusted to the greatest degree of nicely, and consequently greater power may be developed than with a construction where the mixture is less perfect. The adjustment is quickly effected preferably by providing 20 a thumb screw T for clamping the bearings Q in position.

While I have described a specific construction of mechanism intermediate the valve operating rod and the separate valves F and 25 G, it is obvious that this may be modified without departing from the spirit of my invention—for instance, in Fig. 3 is illustrated diagrammatically a modified construction, in which F' G' are the separate 30 air and gas valves, H' the rod operated by a cam U and a shaft U' of the engine, and V a lever which is rocked by the rod H'. This lever is provided with a pair of segmental arms V' to which are adjustably connected the radius arms W, having their opposite ends attached to bell crank levers X. One arm of each of the bell crank levers X is arranged in parallelism with a rock arm Y, and between these rock arms Y and the 40 arms of the bell cranks are arranged shiftable bearings Z. In operation the valves F' G' are simultaneously operated by the movement of the shaft U', cam U, rod H' and intermediate connections. The amplitude of 45 movement imparted to these valves is dependent, first, upon the position of the intermediate bearing Q, and these may be shifted by an automatic governor, not shown, and, second, the relative degree of movement of 50 the valves may be changed by an adjustment of the radius rods W in the point of connection to the segments V'.

What I claim as my invention is:

1. In an explosion engine, the combination 55 with a mixing chamber, of a plurality of valves for separately and independently controlling the admission of the gaseous ingredients for the explosive mixture to said chamber, and timed operating mechanism 60 for simultaneously seating and unseating said valves adjustable to vary the relative amplitude of movement thereof.

2. In an explosion engine, the combina-

tion with a mixing chamber, of a plurality of valves for separately and independently 65 controlling the admission of the gaseous ingredients for the explosive mixture to said chamber, and timed mechanism for simultaneously seating said valves intermediate 70 suction strokes, said mechanism being adjustable to vary the relative degree of movement of said valves.

3. In a gas engine, the combination with a plurality of valves for separately controlling the gaseous ingredients forming the explosive mixture, a main admission valve for the explosive mixture, a chamber intermediate said main valve and the valves for the separate ingredients, timed mechanism for simultaneously seating and unseating all of 80 said valves, and means for varying the amplitude of movement of the ingredient controlling valves.

4. In an explosion engine, the combination with a mixing chamber having separate air and gas admission ports thereto, valves respectively controlling said admission ports, a common timed actuating mechanism for simultaneously unseating and seating said valves at the beginning and ending 90 of each suction stroke, and means for relatively varying the amplitude of movement of said valves.

5. In an explosion engine, the combination with a mixing chamber having separate admission ports for air and gas respectively controlling said ports, a common timed actuating mechanism for simultaneously unseating and seating said valves at the beginning and ending 100 of the suction stroke, and intermediate connections between said common actuating mechanism and the respective valves whereby their relative degrees of movement may be adjusted without changing the timing.

6. In an explosion engine, the combination with an admission valve, of an adjustable actuating mechanism therefor comprising a pair of coöperating rock arms and an adjustable bearing on one of said arms for 110 variably contacting with the other arm.

7. In an explosion engine, a pair of valves, a rockable member for simultaneously actuating said valves, separate intermediate rockable members for transmitting the 115 movement of said first mentioned member to the respective valves, and adjustable bearings for varying the point of contact of said first mentioned rockable member upon the respective intermediate rockable members. 120

8. A valve actuating mechanism comprising a reciprocatory rod, a rock shaft actuated thereby, a second rock shaft, compound levers for transmitting movement from the first to the second rock shaft, a pair of rock 125 arms on said second rock shaft, a pair of

bell-crank levers, and adjustable bearings forming contacts for said bell cranks with the respective rock arms on said second rock shaft.

5 9. In an explosion engine, the combination with a timed admission valve, of correspondingly timed valves for separately controlling the admission of the air and gas, and means for adjusting the relative ampli-

tudes of movement of said valves without 10 changing the timing thereof.

In testimony whereof I affix my signature in presence of two witnesses.

NORMAN T. HARRINGTON.
